N. J., a corporation of New Jersey

Application February 12, 1930, Serial No. 427,935

15 Claims. (Cl. 123—179)

This invention relates to starting apparatus for internal combustion engines.

One of the objects of the invention is to provide novel engine starting mechanism that is light, compact, and efficient and is adapted for manual actuation, power actuation, or both manual and power actuation.

A further object is to provide an engine starter which embodies a small, compact, and efficient multi-cylinder fluid pressure engine as power actuating means, and which also includes additional means for manual operation of the starter.

A still further object is to provide an engine starter which embodies both fluid pressure power cranking means and manual cranking means which are automatically brought into cranking engagement with the engine, and a booster magneto effective during operation of the starter to augment or displace the normal ignition means of the engine being started.

These and other objects will appear more fully in the detailed description of the invention which follows.

One embodiment of the invention is illustrated in the accompanying drawings showing in Fig. 1 a longitudinal view, partly in section, of one form of starting mechanism and in Fig. 2 a transverse sectional view along the line 2—2 of Fig. 1, but it is to be expressly understood that these drawings are for the purpose of illustration only and are not to be construed as a definition of the limit of the invention, reference being had for this purpose to the appended claims.

As shown, the engine starter of the present invention is of the type wherein a driving or engine-engaging member, adapted for automatic advancement into cranking engagement with a member of the engine to be started, may be actuated by either power or manual means through a suitable train of reduction gearing and other drive transmission means, the power means being entirely independent of electrical energy for its operation.

In the illustrated embodiment, the driving member, drive transmission means, and reduction gearing are suitably supported and housed within a casing section 2 which is detachably connected to the housing 3 of the engine to be started, by suitable means such as screws 4, and the power and manual actuating means are in turn suitably housed and supported in a second casing section 5, which is detachably connected to casing section 2 by any suitable means (not shown). Housing portion 5 is open at its outer end and provided with an irregularly shaped end

plate 6 that is detachably secured thereto by any suitable means such as screws 7.

The power actuating means preferably comprise a suitable fluid pressure engine, the rotation of the engine shaft being suitably transmitted to the reduction gearing. In the form shown, a plurality of radially arranged cylinders, one of which is shown at 8, are secured by any suitable means (not shown) to the outer end of casing 5, the upper ends of the cylinders extending radially from the casing. There may be any suitable number of these cylinders arranged singly or in pairs, but preferably three cylinders are employed.

Each cylinder 8 is provided with a piston 9 which is connected to a crank shaft 10 by means of the usual wrist pin 11 and connecting rod 12. Crank shaft 10 extends longitudinally substantially the length of casing 5 and is rotatably supported by ball bearings 13 in a boss 14 formed in said casing. Crank shaft 10 is provided at its inner end, adjacent casing 2, with a pinion 15 for engagement with the reduction gear train, later to be described, and at its outer end with a single crank pin 16 to which all three connecting rods 12 are secured in a well known manner, each connecting rod being provided with an arcuate shoe 17 which bears against a bearing sleeve 18, the latter sleeve being placed over a bushing 19 surrounding crank pin 16. A pair of connecting rod rings 20 are then placed over the ends of shoes 17 thus retaining them in operative relation with the crank pin. This crank pin assembly is held in its proper position on the pin by any suitable means such as a washer 21 and screw 22 which is threaded into the end of crank pin 16, a locking clip 23 being provided between washer 21 and the head of screw 22 to prevent unthreading of the latter. A counterweight 24 is formed on crank shaft 10 to balance the crank pin assembly.

Suitable means are provided for supplying and exhausting a motive fluid to the above described fluid pressure engine, said means, in the present embodiment, comprising passageways disposed within casing 5 and cylinders 8 and utilizing crank shaft 10 as a distributing valve. As shown, each of the cylinders 8 is provided with a channel 25 opening into the top of the cylinder, which is a continuation of a similar channel 26 formed in casing 5. These channels act as both intake and exhaust passages for the cylinders. A main supply passage 27 and an exhaust passage 28 are also provided, supply passage 27 being formed in end plate 6 and suitably connected to

a source of fluid under pressure (not shown), such as a compressed air tank, while exhaust passage 28 may be located in casing 5 and may discharge directly into the atmosphere. Supply passage 27 opens directly into the crank case of the fluid pressure engine, thereby creating a force effective upon the inner surface of each of the pistons 9, which force is effective to drive the pistons outwardly in proper succession as the channels 26 for the respective cylinders are brought successively into communication with the exhaust 28, the said passages 26 and 28 leading to the interior of boss 14 within which crank shaft 10 is journaled. Each passage 26 is provided with two branches at its inner end, one supply branch 26^a and one exhaust branch 26^b. Interposed between the interior of the boss and the crank shaft, and fixedly secured to the former, is a valve bushing 29 which is provided with a plurality of ports adapted to register with the respective passages in casing 5. A main exhaust port 30 registers with passage 28 and extends annularly around the interior of bushing 29. A plurality of supply ports 31^a and exhaust ports 31^b register with passages 26^a and 26^b, respectively.

Crank shaft 10, which extends within bushing 29 and rotates relative thereto, is provided with a plurality of ports and passages such that as it rotates within bushing 29 it performs the function of a distributing valve. For this purpose a hollow bore is provided within crank shaft 10, extending substantially the length of bushing 29, and divided into two portions, 32^a and 32^b, by any suitable means such as a screw plug 33. Portion 32^a opens into the crank case and acts as a supply passage, while portion 32^b is closed at both ends and forms a part of the exhaust passage. The crank shaft is provided with a supply port 34 which is adapted to connect the hollow bore portion 32^a successively with the various supply ports 31^a, so that the motive fluid may be supplied from the crank case and distributed to the respective cylinders of the starter engine. Crank shaft 10 is also provided with a relatively large exhaust port 35 which cooperates with ports 31^b for permitting the cylinders to exhaust into the hollow bore portion 32^b of the crank shaft, and a pair of exhaust ports 36 which are always in communication with the annular exhaust port 30 of the valve bushing permit the exhaust fluid to pass to the atmosphere. As above stated, the exhaust port 35 is relatively large, and is preferably of such a width as to permit a suitable degree of overlapping; that is, each successive channel 26 is preferably opened to communication with the atmosphere just prior to the cut off of the preceding channel 26. Such overlapping, although not essential, is nevertheless desirable in that it permits a smoother application of power to the crankshaft.

In the operation of the fluid pressure engine above described, the motive fluid, such as air under pressure, is supplied to the crank case through main supply passage 27, and passes through hollow bore portion 32^a and port 34 in crank shaft 10 to one of ports 31^a, and thence through passages 26^a, 26 and 25 to one of the cylinders. As the piston in said cylinder is drawn downward by expansion of the motive fluid acting upon the inner surfaces of the other pistons, crank shaft 10 is rotated until, after approximately 180° of rotation, port 35 registers with the proper port 31^b and the fluid within the cylinder is allowed to exhaust to the atmosphere

through passages 25, 26 and 26^b, ports 31^b and 35, hollow bore 32^b, exhaust ports 36 and 30, and passage 28. Such exhaust reduces the pressure above piston 9, thereby permitting an upward power stroke of the piston by the force of the motive fluid in the crankcase which constantly acts upon the under surface of each piston. As crank shaft 10 rotates this cycle of operation is repeated in succession for the respective cylinders.

The rotation of crank shaft 10 is transmitted to the driving or engine-engaging member by suitable means including a train of reduction gearing and other drive transmission means including a yielding clutch. The reduction gearing, in the embodiment shown, comprises a large external gear 37 which meshes with pinion 15 secured to crank shaft 10, said gear being drivably connected in any suitable manner to the inner end of a shaft 38 as by means of two flattened sections formed on the inner surface of the hub of the pinion and adapted to register with two correspondingly flattened surfaces on shaft 38, these flattened surfaces forming a double-D 39. Shaft 38 extends the entire length of casing 5 and is rotatably supported therein by any suitable means such as a pair of bosses 40 and anti-friction bearing sleeves 41. Formed integral with the hub of gear 37 is a pinion or sun gear 42 which meshes with a plurality of planetary gears 43, preferably three in number only one of which appears in section in the drawings, the planetary gears in turn engaging with a stationary internal ring gear 44 secured to the interior of casing 2 in any suitable manner as by means of studs (not shown). A dowel pin 45 preferably extends into casing 2 and ring gear 44 to prevent shearing of the studs. Planetary gears 43 are journaled on bushings 46 surrounding screws 47 which are threaded into an end plate 48 of the drive transmission means, later to be described, and are held in proper operative position by an annular retaining ring 49.

The drive transmission means, in the embodiment shown, comprises an end plate 48 which is rotatably supported in casing 2 by any suitable means, and which receives its rotation from crank shaft 10 through the reduction gearing previously described. Rigidly secured to end plate 48 as by rivets 50 is a cup-shaped barrel member 51, within which barrel member and drivably connected thereto by any suitable means, such as a friction clutch, there is provided an interiorly threaded nut 52. In the form shown, the yielding driving connection between these two members comprises a plurality of friction disks 53 splined alternately to the interior of barrel member 51 and the exterior of nut 52. These friction disks bear at one end against an annular spacing member 54 held in operative position by the outwardly turned ends 55 of the splines or nut 52, and are held in frictional engagement with one another by means of a plurality of coil springs 56 bearing against a thrust plate 57 through which the force of the springs is transmitted to a spacing member 58 and the friction disks 53. A lock ring 59 surrounds the end of the clutch assembly to maintain the parts in assembled relation when other parts of the mechanism are removed. The tension of springs 56 may be adjusted by means of a nut 60 which is threaded onto the end of nut 52. A ring 61 provided with studs 62 may be employed to maintain the coil springs 56 in spaced relation around the nut.

Suitable means are provided for transmitting 75

the rotation of nut 52 to a driving or engine-engaging member 63, and for moving the latter axially into engagement with a corresponding member 64 of the engine to be started. Accordingly, an exterior threaded shaft 65 is positioned within the interiorly threaded nut 52, said shaft being provided on its outer end with a stop nut 66, and having its inner end exteriorly splined to engage a splined hub 67 on driving member 63. Shaft 65 is hollow and a rod 68 extends therethrough having a nut 69 at its outer end which bears against the end of shaft 65, said rod extending at its inner end through driving member 63 and being provided with a slotted nut 70, limiting the outward movement of driving member 63. A coil spring 71 surrounding the inner end of rod 68 is seated in a recess 72 formed in shaft 65 and bears against the back of driving member 63, thus resiliently urging the latter outwardly towards engine member 64.

An oil sealing member 73 is suitably secured between the flanges of casing 2 and engine casing 3 and surrounds driving member 63 and the inner end of the transmission driving means to prevent oil from leaking from within engine casing 2 back into the starting mechanism, and preferably member 73 also carries the means for causing automatic advancement of driving member 63 into engagement with engine member 64 upon rotation of nut 52. In the form shown, said means comprise a two part ring 74 which is held in frictional engagement with a lip 75 formed on oil sealing member 73 by means of a coil spring 76, said ring 74 being provided on its interior surface with lugs 77 which are adapted to engage corresponding notches 78 formed in the periphery of driving member 63. The frictional resistance to rotation of ring 74 tends to retard driving member 63 and shaft 65 with respect to nut 52 when the latter rotates, and to cause relative rotation therebetween, the threaded engagement between shaft 65 and nut 52 being such that the shaft travels to the right, as seen in Fig. 1, until stop nut 66 engages a suitable shoulder 79 formed interiorly of the nut 52, whereupon the shaft and nut rotate together. Movement of shaft 65 to the right, due to relative rotation between it and nut 52, compresses spring 71 which resiliently urges driving member 63 inwardly to the right into engagement with engine member 64 until a clutch jaw 80 formed on driving member 63 engages a similar clutch jaw 81 formed on engine member 64. When the engine to be started starts under its own power, clutch jaw 81 overruns clutch jaw 80 and the inclined faces of the jaw teeth are effective to cause the driving member 63 to be moved outwardly or to the left out of engagement with engine member 64.

In addition to the power actuating means above described, it is desirable that means be provided whereby the starter may be actuated manually. For this purpose shaft 38 is extended outwardly of end plate 6 and is provided at its outer end with a pin 82 adapted to receive a hand crank (not shown). In the illustrated embodiment of the invention, means are likewise provided for manually cranking the starter from one side thereof, said means comprising a shaft substantially at right angles to shaft 38 and mounted in suitable bushings in casing 5, said shaft having at its inner end a bevel gear 83 held thereon by a nut 84 and meshing with a similar bevel gear 85 drivably secured to shaft 38 adjacent gear 37 by double-D 39.

In order to prevent injuries from backfire, suit-

able means may be employed to prevent reverse rotation of the cranking shafts, said means preferably comprising suitable ratchet mechanism mounted on either or both of said shafts. In the form shown, as exteriorly splined hub 86 is keyed to shaft 38 as at 87, and is held longitudinally thereon by means of a shoulder 88. A ratchet member 89 is splined to hub 86 and is resiliently urged into engagement with a cooperating ratchet member 90, mounted on a plate 91, by means of a coil spring 92 interposed between ratchet member 89 and a spring plate 93 which is also splined to hub 86 and bears against a shoulder 94 formed thereon. Plate 91 which carries ratchet 90 is detachably connected to end plate 6 by means of screws 95, and a dowel pin 96 is inserted through both plates 91 and 6 to prevent shearing of screws 95 due to thrust on the ratchet teeth. The ratchet members permit free rotation of either or both cranking shafts in one direction to actuate the driving member, but in case of backfire both shafts are prevented from rotating in a reverse direction.

It is also desirable, in some instances, to operate a booster magneto from the starter mechanism when the engine is being started so as to insure proper ignition and quick starting, and such a magneto, may be drivably connected to the reduction gear train so as to be rotated at a high speed during the cranking operation. In the present embodiment, a booster magneto 97 of any suitable type is mounted on a plate 98, preferably formed integral with casing 5, and held thereon by any suitable means. The shaft 99 of the magneto carries a clutch member 100 that is keyed thereto at 101 and is held thereon by a washer 102 and a nut 103 threaded on the end of the shaft. Clutch member 100 is provided with a plurality of teeth 104 which engage corresponding notches 105, formed in a second clutch member 106 which is rotatably mounted in a boss 107 formed in casing 5. A short shaft 108 is made integral with clutch member 106 and has gear teeth formed on its surface intermediate its ends, constituting a pinion 109 which meshes with gear 37. The end 110 of shaft 108 is journaled in a suitable bearing recess formed in a plate 111 secured to casing 2 by any suitable means. Pinion 109 and gear 37 constitute driving connections driven either by the fluid pressure engine or by the hand cranking shaft, and housed within the starter casing, to which shaft 99 of the booster magneto, which is detachably mounted on the exterior of said casing, may be drivably connected by means of clutch members 100 and 106.

The operation of the apparatus is as follows: When it is desired to crank the engine with which the starter is associated, either the power or manual actuating means may be utilized. If power is to be used a motive fluid under pressure is supplied to the fluid pressure engine through the main supply passage 27, and the fluid pressure engine is operated thereby as previously described. Rotation of crank shaft 10 of the fluid pressure engine is then transmitted by pinion 15 through the train of reduction gearing to barrel member 51. The interiorly threaded nut 52 rotates with barrel member 51 due to the yielding driving connection therebetween formed by the friction clutch, and owing to the frictional drag of ring 74, as previously described, relative rotation between nut 52 and shaft 65 occurs, causing the latter to move to the right, compressing spring 71 and yieldingly moving 75

driving member 63 inwardly into engagement with engine member 64.

Should it be desired to crank the engine to be started manually, a cranking handle is fitted to the end of shaft 38, or the other cranking shaft at right angles thereto, and is rotated in the proper direction. The rotation of shaft 38 is transmitted through pinion or sun gear 42 to the remainder of the reduction gear train and to the driving member 63 in a manner similar to that above described for power operation. In case the engine backfires, shaft 38 is prevented from rotating in the reverse direction by ratchet members 89 and 90, and slippage between the friction disks 53 prevent breaking of any of the starter parts.

As soon as the engine starts under its own power, engine jaw 81 overruns starter jaw 80 and forces driving member 63 back to its original position shown in the drawings.

When the booster magneto 97 is employed, the rotation of either crank shaft 10 or shaft 38 is transmitted through gears 37 and 109 to the magneto shaft, the latter rotating at a relatively high speed so as to insure proper ignition when the engine is being started. It will be seen that the reduction gearing for operating the magneto is entirely enclosed within the starter casing, and is drivably connected with the magneto shaft by a clutch which extends through the casing. Therefore, when the magneto is unnecessary it may be entirely detached by removing the means securing it to plate 98, and by disengaging clutch members 100 and 106. The starter mechanism, however, remains a complete self-contained unit, the operation of which is in no way affected by the removal or attachment of the booster magneto thereto.

It will be seen from the above description, that there is provided by this invention a starter for internal combustion engines which is entirely independent of electrical energy for its operation, and hence well suited for use in large aircraft where it is desired to avoid a heavy drain upon the batteries during starting. The starter described includes as its power operating means a compact and efficient fluid pressure engine combined with reduction gearing and other drive transmission means for actuating a driving member adapted for automatic cranking engagement with a member of the engine to be started. Separate means are further provided for manual operation of the starter, and for operation of a booster magneto from the reduction gearing of the starter, both of which features are highly desirable in starters to be used in aircraft engines.

It will be obvious that the invention is not limited to the form shown in the drawings, but is capable of a variety of mechanical embodiments. For example, any suitable type of fluid distribution means may be substituted for the specific arrangement shown and described, and any suitable number of cylinders may be employed in the fluid pressure engine. Likewise, other forms of reduction gearing or of clutch mechanism may be substituted for the gear train and magneto driving coupling described herein. Various other changes, which will now appear to those skilled in the art, may be made in the form, details of construction and arrangement of the parts without departing from the spirit of the invention, and reference is therefore to be had to the appended claims for a definition of the limits of the invention.

Certain of the claims herein relate to subject

matter disclosed but not claimed in my co-pending application No. 384,444, now Patent No. 1,953,717, granted April 3, 1934. On the other hand there are certain features disclosed herein but not claimed, as they constitute the subject matter of claims in co-pending applications of Romeo M. Nardone filed March 22, 1930 and February 14, 1935, bearing Serial Numbers 438,220 and 6,555 respectively.

What is claimed is:

1. A starter for internal combustion engines, comprising a fluid pressure engine having a plurality of cylinders radially arranged, a driving member adapted to engage and crank a member of the engine to be started, means including a gear train and a friction clutch for drivably connecting said fluid pressure engine and said driving member, and means operatively connected to said gear train for preventing backward rotation of said gear train.

2. In apparatus of the class described, the combination of a fluid pressure engine having a crank shaft and a plurality of radially arranged pistons connected to a common crank pin of said crank shaft, a train of reduction gears operatively connected to said crank shaft, a driving member adapted to be driven by said engine through said gear train, a yielding clutch interposed between said gear train and said driving member, and means drivably connected to said gear train for preventing backward rotation of said engine crank shaft.

3. Starting mechanism of the class described comprising a driving member adapted to be moved into engine-cranking position, a manually operable cranking shaft extending coaxially with said member, means including reduction gearing drivably connecting said shaft and member, a pair of shafts mounted substantially parallel to said cranking shaft and drivably connected with said gearing, a booster magneto having an armature drivably connected to one of said pair of shafts, and a radial fluid pressure engine drivably connected to the other of said pairs of shafts.

4. Starting mechanism for internal combustion engines comprising a rotatable driving member adapted to engage and crank a member of an engine to be started, a manually operable cranking shaft, means including gearing drivably connecting said cranking shaft and member, said member, shaft and gearing being concentrically arranged, a pair of countershafts parallel to but spaced laterally from said cranking shaft, said countershafts being drivably connected to said gearing, a booster magneto having an armature coaxial with and drivably connected to one of said countershafts, and a radial fluid pressure engine coaxial with and drivably connected with the other of said countershafts.

5. Starting mechanism for internal combustion engines comprising a driving member movable to engage and crank a member of an engine to be started, a manually operable cranking shaft arranged coaxially with said member, a reduction gear train arranged concentrically with said shaft and drivably connecting the same with said member, means for moving said member into engine-engaging position on rotation of said cranking shaft, a radial fluid pressure engine having a driven shaft parallel to said cranking shaft and drivably engaging said gearing, and a booster magneto having an armature shaft parallel to said cranking shaft and drivably engaging said gearing.

6. In engine starting mechanism, the combination of a driving member adapted to engage and crank a member of an engine to be started, a manually operable cranking shaft extending coaxially with said member, means including a reduction gear train concentric with said shaft and drivably connecting the same with said member, means for automatically shifting said member to cranking position on rotation thereof, a fluid pressure engine having a crank shaft and cylinders arranged radially around said crank shaft, said crank shaft extending parallel to but being spaced laterally from said cranking shaft, and means drivably connecting said crank shaft with said gearing.

7. Engine starting apparatus for internal combustion engines comprising a driving member shiftable into engine cranking position, a manually operable cranking shaft mounted coaxially with said member, means mounted concentrically with said shaft and member for drivably connecting the same, said means including reduction gearing and a yieldable driving connection, a radial fluid pressure engine having a rotating crank shaft, and means drivably connecting said crank shaft with said gearing, and means on said cranking shaft for preventing reverse rotation of said crank shaft.

8. In an improved engine starting mechanism comprising in combination, an engine engaging member, means including a gear train for actuating said engine engaging member, and a plurality of cranking shafts drivably connected to said gear train, two of said shafts being disposed with their axes lying in planes whose intersection coincides with the axis of a third of said cranking shafts.

9. In an improved engine starting mechanism comprising in combination, an engine engaging member, means including a gear train for actuating said engine engaging member, a plurality of cranking shafts drivably connected to said gear train, two of said shafts being disposed with their axes lying in planes which intersect in the axis of rotation of said engine engaging member, and a third cranking shaft in coaxial alignment with said engine engaging member.

10. In an improved engine starting mechanism comprising in combination, an engine engaging member, means including a gear train for actuating said engine engaging member, a plurality of cranking shafts drivably connected to said gear train, two of said shafts being disposed with their axes lying in planes which intersect in the axis of rotation of said engine engaging member, and a third cranking shaft having its axis parallel to that of one of said first named cranking shafts.

11. In an improved engine starting mechanism comprising in combination, an engine engaging member, means including a gear train for actuating said engine engaging member, and a plu-

rality of cranking shafts drivably connected to said gear train, two of said shafts being disposed with their axes lying in the planes whose intersection coincides with the axis of a third of said cranking shafts, and means cooperating with one of said shafts for locking all three shafts against backward rotation in the event of a backfire of the engine being cranked.

12. In an improved engine starting mechanism comprising in combination, an engine engaging member, means including a gear train for actuating said engine engaging member, a plurality of cranking shafts drivably connected to said gear train, two of said shafts being disposed with their axes lying in planes which intersect in the axis of rotation of said engine engaging member, a third cranking shaft in coaxial alignment with said engine engaging member, and means cooperating with one of said shafts for locking all three shafts against backward rotation in the event of a backfire of the engine being cranked.

13. In an improved engine starting mechanism comprising in combination, an engine engaging member, means including a gear train for actuating said engine engaging member, a plurality of cranking shafts drivably connected to said gear train, two of said shafts being disposed with their axes lying in planes which intersect in the axis of rotation of said engine engaging member, a third cranking shaft having its axis parallel to that of one of said first named cranking shafts, and means cooperating with said shaft for locking all three shafts against backward rotation in the event of a backfire of the engine being cranked.

14. In a fluid motor, a piston, a cylindrical crankcase, a crankshaft leading from said crankcase to a part to be driven, a manually operable shaft extending through said crankcase, and common means interposed between said crankshaft and manually operable shaft to connect both said shafts with said part to be driven, said last named means being constituted by a pair of intermeshed gears, one secured to the end of said manually operable shaft, and the other integral with said crankshaft.

15. Hand starting mechanism for internal combustion engines comprising in combination a housing, a clutch member mounted therein and adapted to be shifted into engagement with a member of the engine to be started, a cranking shaft mounted coaxially of said clutch member, means drivably connecting said cranking shaft and clutch member, a magneto mounted on said housing, means drivably connecting said magneto and said cranking shaft, means mounted on said shaft to prevent rotation of said shaft in one direction, a second cranking shaft arranged substantially at right angles to said first cranking shaft, and intermeshing gears carried by said shafts.

RAYMOND P. LANSING.
